COMBINED SIREN AND EMERGENCY WARNING LAMP

Philip H. Stevens, Syracuse, David O. Chase, Camillus,
Roderick F. Bunyea, Skaneateles, and Alan W. Brown-
lie, Syracuse, N.Y., assignors to R. E. Dietz Company,
Syracuse, N.Y.

Filed Dec. 4, 1962, Ser. No. 72,719

Term of patent 14 years

(Cl. D72—1)

Fig. 1

Fig. 2

Fig. 3

Fig. 4

Fig. 5

FIGURE 1 is a top plan view of a combined siren and emergency warning lamp, embodying our new design;

FIGURE 2 is a front elevation thereof;

FIGURE 3 is a fragmentary side elevation thereof, the other side being a mirror image of the side shown;

FIGURE 4 is a fragmentary rear elevation thereof; and

FIGURE 5 is a bottom plan view thereof.

The dominant features of our design reside in the portions shown in full lines.

We claim:

The ornamental design for a combined siren and emergency warning lamp, substantially as shown and described.
